SANITARY FIXTURE

Raymond E. Crane, Kittanning, Pa.

Application October 7, 1929, Serial No. 397,969

7 Claims. (Cl. 4—7)

This invention relates to certain improvements in sanitary fixtures, and particularly to a novel form of seat for a closet bowl in combination with a combined hinge and water supply pipe for pivotally securing the seat to the bowl. More specifically the present invention comprises a closet seat, provided at its rear portion with a transversely disposed passageway and a forwardly and upwardly directed passageway in communication with the transverse passageway, said transverse passageway being in turn, in direct communication with a source of water supply through a manually controlled valve.

15 These passageways are preferably provided with metallic tubular linings, and the tube or the like for the transverse passageway forms in addition a means for pivotally supporting the seat on the closet bowl.

20 One of the objects of this invention is to provide a construction of neat and novel form wherein a bidet is incorporated in the closet seat per se, resulting in eliminating all exposed nozzles or similar piping or obstructions and thus greatly simplifying the cleaning of the seat and bowl and obviously producing a far more sightly and sanitary fixture than heretofore used and provided in prior devices of this character, as disclosed in applicant's Patent No. 30 1,690,478 over which this present structure is an improvement.

A further object of the invention is the provision of a bidet construction that can be applied to the usual closet bowl with slight alterations, by merely substituting this improved form of seat for the old conventional seat as at present used.

35 By this construction, to be more fully hereinafter described, both the upper and lower faces of the closet seat are clear of any mechanical or metal fixtures such as nozzles, piping or hinges and therefore there is nothing to interfere with the maintaining of the seat in an absolutely clean and sanitary condition.

40 A further object is accomplished, in that, with this improved construction the seat can be mounted in closer contact with the bowl than in those construction wherein the nozzle is mounted below the seat and between the bottom 45 of the seat and the top of the bowl.

In addition the provision of a bidet in combination with a closet bowl is greatly simplified by the present invention, and as a matter of fact this combined fixture can be installed with 50 less trouble and expense than the conventional closet seat.

In the accompanying drawing:

Figure 1 is a perspective view of the assembled device;

60 Fig. 2 is an enlarged sectional view showing

the manner of enclosing the piping within the rear portion of the seat; and

Fig. 3 is a plan view.

Referring to the drawing in detail the invention comprises an improved form of seat 1 having embedded in its rear portion a transverse pipe section 2 and a forwardly projecting discharge pipe 3 provided with a slightly upturned outlet end portion 4. The transverse pipe section 2 extends out beyond both edges of the seat 1 to provide a means for hinging the seat to the bowl. This is accomplished by supporting the ends of the pipe section 2 by hinge posts 5 having the lower ends thereof screw threaded and mounted in the rear portion of the closet bowl. One end of the transverse pipe section 2 is closed and the other end is provided with an extension 6 so constructed as to form a water tight rotatable slip joint connection with a gland nut or the like 7, properly packed to 15 maintain a fluid tight connection during the rotation of the pipe section 2 and its extension 6 within said joint.

Transverse pipe section 2 and its extension 6 is connected to a source of water supply 8 through a hand controlled valve 9 whereby upon the opening of the valve water will be directed through the transverse pipe section 2 and discharge pipe 3, into the bowl.

In the preferred embodiment of the invention 30 the transverse pipe section 2 and discharge pipe 3 are preassembled, there being a screw threaded connection between said pipes as shown at 10 and this joint is thereafter securely soldered or similarly fastened in addition to the threaded 35 connection.

This assembled fitting is then molded into the seat, said seat being preferably constructed of any suitable plastic material such as hard rubber and the like whereby the transverse pipe section 2 and discharge pipe 3 will be permanently 40 mounted within the rear end of the seat.

With the constructions above outlined the transverse pipe section 2 not only forms a means of supplying the water to the nozzle opening 4 but also provides a very simple efficient and convenient means for hingedly connecting the seat to the bowl without requiring any additional fixtures other than the hinge posts 5 anchored 45 in the rear portion of the bowl.

50 What is claimed as new is:

1. A closet seat having formed integrally with the rear portion thereof, a forwardly directed and upwardly curved tubular nozzle and means 55 for connecting said nozzle with a source of water supply.

2. A closet seat having formed integral with the rear portion thereof, a passageway comprising a forwardly and upwardly curved nozzle 60

and means for connecting said nozzle with a source of water supply.

3. A closet seat having formed integral with the rear portion thereof, a passageway comprising a forwardly and upwardly curved tubular nozzle and means for connecting said nozzle with a source of water supply.

4. A closet seat having formed integrally with the rear portion thereof, a transverse passageway and an intersecting forwardly and upwardly directed passageway and means for connecting said transverse passageway to a source of water supply.

5. A sanitary fixture including a bowl and a seat, a transverse passageway formed integral with the rear portion of the seat, a forwardly and upwardly directed passageway also formed integral with the seat in communication with said transverse passageway and a tubular lining for the transverse passageway in communication with a source of water supply, said tubular lining also providing a means for pivotally connecting the seat with said bowl.

6. A sanitary fixture including a bowl and a seat, a transverse passageway formed integral with the rear portion of the seat, a forwardly and upwardly directed passageway also formed

integral with the seat in communication with said transverse passageway, a tubular lining for the transverse passageway in communication with a source of water supply, said tubular lining also providing a means for pivotally connecting the seat with said bowl and a tubular lining comprising a nozzle for the forwardly and upwardly directed passageway.

7. A sanitary fixture including a bowl and a seat, a transverse passageway formed integral with the rear portion of the seat, a forwardly and upwardly directed passageway also formed integral with the seat in communication with said transverse passageway, a tubular lining for the transverse passageway extending outwardly from the edges of the seat, means for hingedly connecting said extensions to upwardly projecting posts carried by the bowl, means for connecting one of said extensions to a source of water supply, a valve for controlling said water supply and a tubular lining comprising a nozzle for the said forwardly and upwardly directed passageway, whereby upon the manipulation of said valve a stream of water will be directed forwardly into the bowl from the rear of said seat.
